REPAIR PATCH FOR RUBBER

Alois Peter Felden, Munich, Germany, assignor to Stahlgruber Otto Gruber & Co., Munich, Germany

Filed Jan. 5, 1968, Ser. No. 10,067

Term of patent 14 years

Claims priority, application Germany July 11, 1967

Int. Cl. D12—14

U.S. Cl. D90—20

Fig. 1.

Fig. 2.

*Fig. 3.**Fig. 4.*FIGURE 1 is a plan view of a repair patch for rubber showing my new design;

FIGURE 2 is a cross-sectional view taken through FIGURE 1 along the line 2—2;

FIGURE 3 is a plan view of a modified form thereof; and

FIGURE 4 is a cross-sectional view taken through FIGURE 3 along the line 4—4.

The drawing is shaded in black and white to indicate contrasting color.

I claim:

The ornamental design for a repair patch for rubber, as shown and described.
